UNITED STATES PATENT OFFICE.

ASA C. WALKER, OF MOUNT AIRY, GEORGIA, ASSIGNOR OF ONE-HALF TO FRANK M. BOSTON, OF ATLANTA, GEORGIA.

TIE-SPACING DEVICE FOR RAILROADS.

1,349,026.

Specification of Letters Patent. Patented Aug. 10, 1920.

Application filed February 18, 1920. Serial No. 359,742.

To all whom it may concern:

Be it known that I, ASA C. WALKER, a citizen of the United States, residing at Mount Airy, in the county of Habersham 5 and State of Georgia, have invented certain new and useful Improvements in Tie-Spacing Devices for Railroads, of which the following is a specification, reference being had to the accompanying drawings.

10 This invention relates to an improved tie spacing device for railroads and an object is to provide a device of this kind wherein a rail engaging clamp is employed in conjunction with the rail or lifting jacks for 15 spacing ties under the rails, the aim being to position the clamp in engagement with the rail, constituting an abutment for the jack, which is placed between the clamp and the tie, whereby upon manipulation of the 20 jack the tie may be moved.

Another object resides in the provision of a rail clamp, in the form of a rail chair, the rail engaging cavities or cut away faces thereof being beveled on angular planes, 25 whereby the chair or clamp may be disposed in engagement with the rail from underneath in angular positions, so that when one end of the jack engages the clamp or chair, the clamp will wedge in position.

30 A further object resides in the provision of means on the clamp to engage the inner portion of the base of the rail to insure locking the clamp in position, particularly when pressure is applied thereagainst, that 35 is to say locked by causing a wedging action.

While the design and construction at present illustrated and set forth is deemed preferable, it is obvious that as a result of a reduction of the invention to a more practical 40 form for commercial purposes, the invention may be susceptible to changes, and the right to these changes is claimed, provided they are comprehended within the scope of what is claimed.

45 The invention comprises further features and combination of parts, as will be hereinafter set forth, shown in the drawings and claimed.

In the drawings:

50 Figure 1 is a plan view of a portion of a railroad showing opposite clamps in position acting as abutments for the jacks, which are closed and placed between the clamps and the tie to be moved,

Fig. 2 is a side elevation showing the jack 55 open and the tie as having been moved,

Fig. 3 is a view in elevation of the clamp detached,

Fig. 4 is an end view of Fig. 3,

Fig. 5 is a view of a modified form of 60 clamp; and

Fig. 6 is an end view of Fig. 5.

Referring more especially to the drawings, 1 designates the parallel rails of the track, and 2 the ties thereof, 3 denotes the 65 abutment clamps, and 4 the jacks. Each clamp comprises a body, the base 5 of which engages under the base of the rail, and the upper face of this base is beveled or inclined as indicated at 6, whereby the clamp may 70 be held in an angular position relatively to the rail. Overlying the base 5 of the clamp and projecting from the body thereof is an enlargement 7, which has its under face beveled as indicated at 8, to overlie and engage 75 the upper surface of the base of the rail to permit the clamp to be positioned angularly relatively to the rail. The enlargement 7 near its upper inner portion is cut away as indicated at 9, and is shaped to conform to 80 the contour of the under surface of the ball of the rail. In fact the surface of this cut away portion is beveled correspondingly to the bevels 6 and 8 in order to permit the clamp to be angularly disposed.

85 In the use of the clamp, it is placed in engagement with the rail as shown clearly in Figs. 1, 2 and 3, the clamp being disposed angularly. The jack is disposed so that the 90 foot 10 of the rack of the jack engages the clamp. The head 11 of the body 12 of the jack is disposed in engagement with one of the ties. The operating lever 13 of the jack protrudes upwardly and after the jack is 95 so disposed, the operating lever is manipulated, thereby causing the body and the rack to move in opposite directions. The foot of the rack will bear against the clamp while the head of the body will bear against the tie, and as the two parts of the jack move away from each other, the tie which is engaged by the head of the body of the jack may be spaced in proper position with relation to the adjacent ties. The rack in applying pressure on the clamp will cause the 100 clamp to wedge or bind in engagement with the rail, and thereby constitute a firm abutment.

105

The abutment clamp shown in Figs. 5 and 6 is employed in a similar manner, with the exception that the base of the body of the clamp has an upwardly projecting lug 14 which engages the inner edge of the base of the rail, thereby maintaining the clamp in position more efficiently. With the lug 14 engaging the inner edge of the base of the rail, the clamp will be held firmer, there being less chance for the clamp to become displaced when the pressure is applied.

The invention having been set forth, what is claimed as new and useful is:—

1. In a device of the kind set forth, an abutment clamp comprising a body having a base adapted to engage under the base of the rail, said body having a lateral projection to overlie the base of the rail and engage under the ball of the rail and in contact with the web thereof, said abutment clamp adapted to wedge in engagement with the rail, when pressure is applied thereon when using a jack between the clamp and a tie, the upper face of the base of the clamp and the under face of the projection of the body being correspondingly beveled, where-

by the clamp may be disposed angularly with relation to the rail, to insure its wedging engagement with the rail, said lateral projection having its upper inner portion cut away and beveled to wedge under the ball of the rail.

2. An abutment clamp comprising a body having a base, said body having a lateral enlargement overlying and being spaced from the upper face of the base and having its upper inner portion cut away and beveled, adapted to engage under the ball of the rail, said enlargement being adapted to engage the web of the rail, the upper face of the base and the under face of the enlargement being correspondingly beveled whereby together with the cut away beveled upper part of the enlargement, said abutment clamp may be disposed angularly with relation to a rail, the inner end of the base having upwardly extending projection to engage the inner edge of the base of the rail.

In testimony whereof I hereunto affix my signature.

ASA C. WALKER.
